Barry E. Negrin

(57) **CLAIM**

The ornamental design for a paddle, as shown.

DESCRIPTION

FIG. 1 is a perspective view of a paddle, showing my new design.

FIG. 2 is a left elevational view of the paddle of FIG. 1.
FIG. 3 is a right elevational view of the paddle of FIG. 1.
FIG. 4 is a top elevational view of the paddle of FIG. 1.
FIG. 5 is a bottom elevational view of the paddle of FIG. 1.
FIG. 6 is a front elevational view of the paddle of FIG. 1.
FIG. 7 is a rear elevational view of the paddle of FIG. 1; and,
FIG. 8 is a cross sectional view taken on line 8-8 of the
paddle of FIG. 2.

1 Claim, 6 Drawing Sheets
